Patented Aug. 8, 1922.

UNITED STATES PATENT OFFICE.

THOMAS L. ZOOK, OF LOS ANGELES, CALIFORNIA.

SPINAL-VIBRATING APPARATUS.

1,425,433.

Specification of Letters Patent. Patented Aug. 8, 1922.

Application filed March 2, 1921. Serial No. 449,090.

To all whom it may concern:

Be it known that I, THOMAS L. Zook, a citizen of the United States, residing at Los Angeles, in the county of Los Angeles and State of California, have invented new and useful Improvements in Spinal-Vibrating Apparatus, of which the following is a specification.

It is the object of this invention to provide exercising apparatus particularly adaptable for causing vibration of the spinal column.

The improved apparatus includes members movable relative to one another and having means for causing vibration of one of the same. The vibrated member is also provided with means for cushioning the vibrations and has supporting means connected thereto which are adapted to engage the head of a person using the apparatus. The other of the relatively movable members is provided with means for suspending the same, so that the apparatus may be employed for supporting a user by the head so as to tension the apparatus and the patient during subsequent actuation of the apparatus, to cause vibration of the patient and a consequent rejuvenation of the spinal column.

The invention will be readily understood from the following description of the accompanying drawings, in which—

Figure 1 is a front elevation of the apparatus in use.

Fig. 2 is a detail front elevation of the apparatus partly in vertical section.

Fig. 3 is a side elevation of the device with the upper part thereof shown in vertical section.

The improved vibrating apparatus includes relatively movable frames 1 and 2 shown as U-shaped members reversely arranged with relation to one another and having the frame 2 slidable within the frame 1. Connecting means shown as an eye bolt 3 is secured to the top of U-shaped member 1 so that the mechanism may be suitably suspended. For this purpose a chain 4 is preferably connected to the eye bolt and is adapted to have any one of its links engaged by a hook 5 suitably suspended from a door frame, or from a ceiling 6, or other support.

Pulleys 7 and 8 are journaled one above the other in the frame formed by members 1 and 2. These pulleys are fixed upon bolts 9, and the shaft of the upper pulley 7 is

journaled in the inner frame member 2 and is slidably received in slots 10 provided in outer frame member 1, while the bolt 9 for the lower pulley 8 is slidably received in slots 10 provided in the inner frame member 2 and is journaled in the outer frame member 1. Nuts 11 are threaded upon bolts 9 for preventing displacement of the parts.

The upper pulley is preferably provided with a flat periphery, while the lower pulley has a grooved periphery 12, and a flexible member 13 shown as a sprocket chain is received between the pulleys so as to run in groove 12. The links comprising the sprocket chain make the latter of uneven thickness, so that when the chain is drawn back and forth, the pulleys will be alternately forced away from one another and then again drawn toward one another by the force exerted in opposite directions upon frame members 1 and 2, so as to cause vibration of frame member 2 with relation to frame member 1 suspended as above described. In order to conveniently actuate chain 13, as described, handles 14 are preferably connected to the ends of said chain by connecting members 15.

Supporting means are suspended from the U-shaped member 2 and are shown as a bolt 16 having a loop 17 received through the base of member 2 so that the bolt depends therefrom. A washer 21 is positioned upon the lower end of the bolt by means of nut 19, and a coil spring 20 is received around the bolt with its lower end resting against washer 21 and with a washer 22 received against the upper end of the spring. A sleeve 18 is received around the spring and the washers, and said sleeve is provided with elongated slots 23 adjacent upper washer 22.

A clevis 25 extends below sleeve 18 with the arms thereof bent so as to extend through slots 23 and be received in the upper washer 22. By this arrangement it will be seen that bolt 16 provides a cushioning support for the clevis, so that the vibrations of frame member 2 will be transmitted to the clevis in a somewhat modified form.

Tongs are suspended from clevis 25 preferably by an S-shaped hook 26 received through openings 27 in the arms 28 of the tongs. These tong arms are adjusted relatively to one another by a bar 29 pivoted to one arm and extending through a guide 30 upon the other arm. This guide is provided with a locking pin 31 adapted to engage in

any one of a series of notches 32 provided along bar 29. The collapse of the tong arms is preferably limited by a pin 33 projecting from bar 29 and arranged to engage one of 5 the tong arms.

The tongs preferably carry supporting means to engage the head of a person using the apparatus, and for this purpose rings 35 are arranged at the swinging ends of the 10 tong arms, and straps 36 are supported between the tong arms by hooks 37 at the ends thereof adapted to engage rings 35.

In operation the apparatus having been suspended as above described, the tong arms 15 are collapsed to their limit of movement and the tongs are arranged above the head with one of the straps 36 beneath the chin and the other strap beneath the back of the head at the base of the brain. The apparatus is 20 so suspended as to permit positioning of the parts, as thus described, when the person using the apparatus is standing upright. The patient then rises upon the toes and the tong arms are spread apart and adjustably 25 held in spread position so as to elevate the strap 36 and thereby tension the apparatus and the body of the patient when the weight of the body is suspended from the apparatus. The handles 14 are then grasped and 30 chain 13 is moved back and forth so as to vibrate the mechanism, and as a consequence cause vibration of the patient's head and of the spinal column.

It will thus be seen that I have provided 35 extremely simple but efficient means for exercising and causing vibration of the spinal column of a patient, the apparatus being readily adjustable so as to accommodate persons of different height, and being also so 40 arranged that by employing suspension chains 4 of different length that the apparatus may be employed in connection with a patient either standing, sitting down, or reclining.

45 Various changes may be made without departing from the spirit of the invention as claimed.

What is claimed is:

1. A device of the character described 50 comprising members movable relative to one another, suspension means for one of said members, supporting means secured to the other member, said members having pulleys in juxtaposition and normally 55 drawn toward one another by the weight carried by the supporting means and actuating means extending between said pulleys for vibrating the same and said movable members.

60 2. A device of the character described comprising frames each having a pulley journaled therein, said frames having a connection permitting of sliding movement of 65 said frames relative to one another, each

by the opposite frame for movement of said pulleys toward one another as the frames are drawn apart, suspension means for one of said members, supporting means secured to the other member, and means for vibrating 70 said pulleys.

3. A device of the character described comprising members movable relative to one another, suspension means for one of said members, supporting means secured to the 75 other member, said members having pulleys in juxtaposition and said pulleys being normally drawn toward one another by the weight carried by said supporting means, and an operating member of uneven width 80 drawn between said members for vibrating the same.

4. A device of the character described comprising members movable relative to one another, suspension means for one of said 85 members, supporting means secured to the other member, said members having pulleys in juxtaposition and said pulleys being normally drawn toward one another by the weight carried by said supporting means, 90 an operating member of uneven width drawn between said pulleys for vibrating the same, and handles upon the respective ends of said operating member for moving the latter back and forth. 95

5. A device of the character described comprising members movable relative to one another, suspension means for one of said members, a bolt depending from the other member, supporting means carried by 100 said bolt, a spring between said bolt and supporting means, and means for vibrating said members relative to one another.

6. A device of the character described comprising members movable relative to one another, suspension means for one of said members, a bolt depending from the other member, a spring on said bolt, a clevis engaging the upper end of said spring and depending at the sides thereof, supporting 105 means carried by said clevis, and means for vibrating said members relative to one another.

7. A device of the character described comprising members movable relative to one another, suspension means for one of said members, tongs depending from the other member, supporting means for a person's head carried by the arms thereof, and means for vibrating said members relative to one 115 another, and extending to points adjacent said supporting means so as to be convenient to the person's hands. 120

8. A device of the character described comprising members movable relative to one another, suspension means for one of said members, tongs depending from the other member, supporting means for a person's head carried by the arms thereof, means for locking the arms of said tongs 125 130

in adjustably spaced positions, and means for vibrating said members relative to one another, and extending to points adjacent said supporting means so as to be convenient to the person's hands.

9. A device of the character described comprising members movable relative to one another, suspension means for one of said members, tongs depending from the 10 other member, supporting means for a person's head carried by the arms thereof, means for limiting the collapse of said arms, and means for vibrating said members relative to one another and extending to 15 points adjacent said supporting means so as to be convenient to the person's hands.

10. A device of the character described comprising members movable relative to one another, suspension means for one of 20 said members, tongs depending from the other member, straps connecting the arms

of said tongs, and means for vibrating said members relative to one another and extending to points adjacent said supporting means so as to be convenient to the person's hands.

11. A device of the character described comprising members movable relative to one another, suspension means for one of said members, a bolt depending from the 30 other member, a sleeve on said bolt, a spring within the same and surrounding said bolt, said sleeve having slots in the same, a clevis extending through said slots to engage said spring and depending at the side of said 35 sleeve, supporting means carried by said clevis, and means for vibrating said members relative to one another.

In testimony whereof I have signed my name to this specification.

THOMAS L. ZOOK.
